Fig. 9

FIG. 1 is a perspective view of the vehicle instrument gauge showing my new design, with the mounting bracket in the down position;

FIG. 2 is an elevational view from the front of FIG. 1 with the mounting bracket in the up position;

FIG. 3 is a plan view from the top of FIG. 1 with the mounting bracket in the back position;

FIG. 4 is an elevational view from the right side of FIG. 1 with the mounting bracket in the down position;

FIG. 5 is a plan view from the bottom of FIG. 1 with the mounting bracket in the down position;

FIG. 6 is a perspective view of the dual instrument configuration with the mounting bracket in the down position;

FIG. 7 is a plan view from the top of FIG. 6 with the mounting bracket in the back position;

FIG. 8 is a plan view from the bottom of FIG. 6 with the mounting bracket in the down position;

FIG. 9 is a plan view from the right side of FIG. 6 with the mounting bracket in the up position;

FIG. 10 is a perspective view of the three instrument configuration with the mounting bracket in the down position;

FIG. 11 is a plan view from the top of FIG. 10 with the mounting bracket in the back position;

FIG. 12 is a plan view from the bottom of FIG. 10 with the mounting bracket in the down position; and

FIG. 13 is an elevational view from the right side of FIG. 10 with the mounting bracket in the up position.

The design is characterized by the presence of a concave front panel containing housing edge outline and instrument frame edge outline, all substantially concave within the plane of the front panel, substantially as shown.

I claim:

The ornamental design for a vehicle instrument gauge, as shown and described.
